UNITED STATES PATENT OFFICE.

CHARLES EDWARD GROSS, OF DURBIN, WEST VIRGINIA.

BROOM-HANDLE.

987,981.

Specification of Letters Patent. Patented Mar. 28, 1911.

Application filed June 6, 1910. Serial No. 565,271.

To all whom it may concern:

Be it known that I, CHARLES E. GROSS, a citizen of the United States, residing at Durbin, in the county of Pocahontas and State 5 of West Virginia, have invented certain new and useful Improvements in Broom-Handles, of which the following is a specification, reference being had to the accompanying drawings.

10 This invention relates to certain new and useful improvements in brooms and more particularly to new and novel means for attaching the handle to the body of the broom.

15 The primary object of the invention is to provide a tubular metallic broom handle which is adapted to be inserted into the body of a broom and receive a portion of the broom straw in its end, and means for 20 quickly and securely fastening the handle and the broom body together.

25 A further object is to provide a tubular broom handle and means for securing a broom body to the end thereof, said handle having a removable closure in one end whereby various articles of household use 30 may be carried in said handle.

With these and other objects in view, the 35 invention consists of the novel features of construction and the combination and arrangement of parts hereinafter fully described and claimed, and illustrated in the accompanying drawings, in which—

Figure 1 is a side elevation of a broom constructed in accordance with the present 40 invention; Fig. 2 is an enlarged section showing the means for securing the broom on the lower end of the handle; and Fig. 3 is a section taken on the line 3—3 of Fig. 2.

45 Referring more particularly to the drawings 5 indicates my improved broom handle which is of tubular form and is constructed from a continuous sheet of metal. The lower end portion of this broom handle is circumferentially corrugated, as shown at 6. These corrugations are adapted to receive the binding wire 7 which is wound around the lower end of the handle and the broom straws to secure the broom body 8 and the 50 handle 5 together. As clearly shown in Fig. 2, the broom straws of the center of the body 8 extend into the end of the tubular handle 5 and above the corrugated portion

thereof. These broom straws, as indicated by the numeral 9, completely fill the interior 55 of the lower end of the handle and form a body therefor which prevents the sheet metal being bent as the binding wire 7 is tightly drawn around the same and disposed in the corrugations 6. Thus the wire may be very 60 tightly wound to prevent the broom body becoming detached from the handle without danger of distorting the metallic handle so that it will retain its original shape even when considerable pressure is brought to 65 bear thereon.

The upper end of the handle 5 is provided with internal screw threads which receive the externally threaded tubular shank 10' of a head 10. This removable head provides 70 a convenient handle portion which may be grasped as the broom is manipulated. The head may be unscrewed from the handle and different household articles such as tacks, tack pullers, or dust cloths may be 75 stored therein so that their possible loss is prevented.

From the foregoing it will be seen that I have provided a broom which is simple and light in construction and of great utility to 80 the houseworker.

While I have shown and described the preferred embodiment of my invention, it will be understood that the same may be variously modified without departing from the 85 essential features or sacrificing any of the advantages thereof.

Having thus described the invention what is claimed is:

A tubular broom handle having a peripherally corrugated end portion adapted to be described in a broom body, a portion of the broom straw extending into the end of the tubular handle above the corrugated portion thereof, and the remaining portion 90 of the broom straw being disposed upon the exterior of the end of the handle, and means wound about the straw and engaging in the corrugations of the handle to rigidly secure the broom body to the handle. 95

In testimony whereof I hereunto affix my signature in the presence of two witnesses.

CHARLES EDWARD GROSS.

Witnesses:
